UNITED STATES PATENT OFFICE.

PHILIP J. HARRAH, OF BLOOMFIELD, INDIANA, ASSIGNOR TO HARRAH MANUFACTURING COMPANY, OF BLOOMFIELD, INDIANA, A CORPORATION OF INDIANA.

LIFTING-JACK.

1,087,879.

Specification of Letters Patent. Patented Feb. 17, 1914.

Application filed June 20, 1913. Serial No. 774,840.

To all whom it may concern:

Be it known that I, PHILIP J. HARRAH, of Bloomfield, in the county of Greene and State of Indiana, have invented certain new and useful Improvements in Lifting-Jacks; and I do hereby declare the following to be a full, clear, and exact description of the invention, such as will enable others skilled in the art to which it appertains to make 10 and use the same.

The object of this invention is to provide a simple, compact, durable and comparatively inexpensive lifting jack having means whereby reversal of travel may be easily 15 effected.

In the accompanying drawings, Figure 1 is an elevation showing the pawls set for lifting. Fig. 2 is a similar view showing the pawls set for lowering. Fig. 3 is a transverse 20 sectional view on line 3—3 Fig. 1. Fig. 4 is a section on line 4—4 Fig. 1. Fig. 5 is a detail of one of the locking pawls.

Referring to the drawings, 1 designates a vertically-disposed rack bar which extends upwardly from a base piece 2, and which is provided on its edges with teeth 3. 25 4 is a casting or housing which is formed with openings to accommodate the rack-bar, and is also provided with horizontal extensions 5 and 6 which extend laterally therefrom on opposite sides of the rack-bar, and either of which may be caused to engage the object to be raised. To this casting is fulcrumed the forked end of a lever 7, and 30 on opposite sides of the fulcrum of this lever are pivoted the lower ends of two pawls 8 which are normally drawn in against the teeth of the rack-bar by a coiled spring 9 which is located within a recess 35 formed by an outwardly-bulged portion 10 of the forked end of the lever. By rocking the latter on its fulcrum these pawls will climb the rack-bar and effect a step by step movement of the casting.

45 12 designates a vertically movable slide mounted on one side of the casting, being held thereto by a bolt 13 which extends from the casting through a longitudinal slot in the slide, and this bolt also forms the pivot 50 for a cam 14 which is designed to engage an outwardly projecting flange 15 at the upper end of the slide so as to raise the latter into its inactive position as against the tension of a coiled spring 16. This slide has laterally 55 extending wings 17 which are in the

plane of beveled edges 18 of the pawls. When the slide is moved by its spring into its lowered position, as in Fig. 2, after the cam has been shifted, the wings of the slide will engage the beveled edges of the pawls 60 so as to prevent them from entering between the rack teeth when moved upwardly by the lever, and hence effect the downward travel of the casting. The slide is also provided with a depending extension 20 which bears 65 against one of the sides of the forked lever.

From what has been said it will be seen that I have provided an extremely simple lifting jack which is not liable to readily get out of order. By merely shifting the 70 cam, so as to throw the spring-impelled slide out of or into operation, the device may be changed so as to travel either upwardly or downwardly. It will also be observed that by providing the casting with the oppositely extending horizontal rests, a wider 75 range of usefulness is obtained.

I claim as my invention:

1. A lifting jack comprising a rack-bar having teeth in its opposite edges, a movable housing fitted on said rack-bar and having a horizontal extension for engaging the thing to be operated upon, a lever having a forked end fulcrumed on said housing, pawls on opposite sides of the fulcrum of the lever, 80 a spring connecting said pawls and inclosed by said forked end, a vertically movable slide mounted on said housing and having laterally extending wings for engaging said pawls to reverse the operation thereof, a 85 spring acting on said slide, and a cam mounted on said housing for holding said slide raised with the wings out of engagement with said pawls.

2. A lifting jack comprising a rack-bar having teeth in its opposite edges, a movable housing fitted on said rack-bar and having a horizontal extension for engaging the thing to be operated upon, a lever having a forked end fulcrumed on said housing, pawls 95 pivoted at their lower ends to said lever on opposite sides of the fulcrum of the lever, a spring connecting said pawls and located within and wholly inclosed by said forked end, a vertically movable slide mounted on 100 said housing and having laterally extending wings for engaging said pawls to reverse the operation thereof, a spring acting on said slide and a cam mounted on said housing for holding said slide raised with 105 the wings out of engagement with said pawls.

110

the wings out of engagement with said pawls.

3. A lifting jack comprising a rack-bar having teeth in its opposite edges, a movable housing fitted on said rack-bar and having oppositely extended horizontal rests, a lever having a forked end fulcrumed on said housing, one side of said forked end having a bulged portion, pawls pivoted at their lower ends to said forked end on opposite sides of the fulcrum of the lever, a spring connecting said pawls located in said bulged portion, a vertically movable slide having a

slot and provided with lateral wings for engaging said pawls, a spring acting downwardly on said slide, a bolt mounted on the housing and extended through said slot, and a cam pivoted on said bolt for engaging said slide to hold it in its inactive position. 15

In testimony whereof, I have signed this 20 specification in the presence of two subscribing witnesses.

PHILIP J. HARRAH.
